HEATER

William M. Hoeffken, Belleville, Ill., assignor to Premier Stove Company, Belleville, Ill., a corporation of Illinois

Filed June 16, 1966, Ser. No. 2,697

Term of patent 14 years

(Cl. D81—19)

FIGURE 1 is a top plan view of a heater incorporating my new design;

FIGURE 2 is a front elevational view thereof;

FIGURE 3 is an end elevational view thereof; the other end being the same; and

FIGURE 4 is a rear elevational view thereof.

The characteristic features of my new design are shown in full lines.

I claim:

The ornamental design for a heater, as shown and described.
